GREETING CARD

Fred Weindel, Jr., Allentown, Pa., assignor to
 L. F. Grammes & Sons, Inc., Allentown, Pa., a
 corporation of Maryland

Application January 13, 1932. Serial No. 586,353

3 Claims. (Cl. 41—10)

This invention relates to personal greeting cards such as are given or exchanged during the Christmas holidays and at other festivals of the year; and it has more particular reference to greeting cards of the folding type.

Greeting cards of the kind specifically referred to have been made heretofore of various materials such as cardboard, paper, parchment, celluloid and unguammed foil, the cards being formed by plain folding of single sheets of these materials.

Broadly speaking, my invention is directed toward the provision of a new and distinctive type of folding greeting card by the use of embossed metal pasted to another material such as cardboard to lend thickness and stiffness and further, to hide the embossing on the back of the metal sheet.

Another object of my invention is to effect the foregoing in such manner as to provide for easy hinge action at the folding point so that the cards may be readily opened and closed repeatedly without straining or rupturing the metal.

Still other objects and attendant advantages will be manifest from the detailed description following in connection with the attached drawing, wherein Fig. I shows the outside face of a greeting card made in accordance with my invention.

Fig. II is a perspective view of the card showing the inside thereof.

Fig. III is a broken out longitudinal sectional view of the card, taken as indicated by the arrows III—III in Fig. I, and drawn to a larger scale; and

Fig. IV is a fragmentary sectional view, corresponding to Fig. III, showing an alternative embodiment of my invention.

The form of my improved greeting card delineated in Figs. I—III of these illustrations, comprises an out side sheet 5 of metal foil with a backing P of paper, which foil may be of brass, aluminum, copper, silver, gold, etc., depending on the color desired; an inside sheet 6 which may be either of like or different metal foil or of fancy paper; and an interposed pair of stiffening or reinforcing sheets 7 and 8 preferably of relatively thick paper, cardboard or other non-metallic material, laid side by side, the several parts being glued or pasted together, and the outer and inner sheets 5, 6 thus united over their normally flat areas.

As shown in Figs. I and III, the out side metal foil sheet 5 has, in the present instance, an area 9 with an embossed ornamental design, and an area 10 of equal size which is plain except for the embossed perimetric bead indicated at 11.

Between the ornamented and plain areas 9 and 10, the out side metal foil sheet 5 is formed with a transverse embossed bead 12, which, at its upper and lower ends, terminates somewhat short of the longitudinal portions of the perimetric bead 11. When made from metal foil, the in side sheet 6 is likewise provided medially of its length with a transverse bead as shown at 13 in Fig. III.

It is to be particularly noted from Fig. III that the stiffening or reinforcing sheets 7 and 8 are slightly narrower than the ornamented and plain areas 9 and 10 of the outside metal foil sheet 5 with consequent provision, between their contiguous side edges of a narrow interval 14 which is bridged by the said outside sheet, as well as by the inside sheet 6.

By virtue of being centralized on the out side and inside sheets 5 and 6, the transverse beads 12 and 13 of necessity fall in direct line with the interval 14 as illustrated in Fig. III. Accordingly, there is formed from the metal foil a central hinge in which the transverse beads 12 and 13 afford an excess of metal at the line of fold so that the card can be easily opened and closed repeatedly without inducing stretch or fracture of the foil. The beading of the outside sheet 5 at 12, as shown, definitely limits its flexure to this hinge zone or portion 12, while at the same time tending to distribute the flexure over the width of this zone 12, and thus obviating local strain-hardening and fracture of the foil by repeated flexure. The bead also accommodates the corresponding portion of the inside facing 6, when the card is folded as well as when it is flat. The narrower width of the inner hinge zone 13 as compared with that of the beaded and curved outer hinge zone 12 affords more ample room for the folding of the inner facing 6 and obviates conflict or reaction of the inner zone 13 with the outer zone 12 in its flexure.

Upon one or both of the smooth faces at the in side of the card may be printed or otherwise inscribed a greeting such as indicated at 15 in Fig. II, with a blank space 16 therebeneath for hand written inscriptions. If metal is used for the inside sheet 6 the figured embellishment may be formed by etching.

Obviously, cards made as described with metallic outside sheets may be finished in a variety of different ways. For example, the embossed areas may be colored in the depressions, and the raised portions polished and thus emphasized by contrast, or they may be burnished or satin finished. Such finishes are of course impossible with paper or cardboard, and my improved cards are thus

definitely distinguished from greeting cards made as heretofore and they are moreover more attractive and durable. It is of course within the province of my invention to emboss the backs of the cards instead of leaving them plain as herein illustrated, or to ornament the cards through perforation with or without embossing and to variously outline the cards—in short to resort to all the artifices ordinarily practiced in embellishing 10 cards of cardboard or paper in accordance with the effects desired.

In the alternative embodiment of Fig. IV, the out side sheet 5a may be like the sheet 5 of the first described embodiment i.e. of paper backed 15 metal foil; while the inside sheet or lining 6a is in this instance of fancy paper which is attached or united (over the normally flat areas) directly to the sheet 5 without interposition of card board 20 stiffening, the said inside sheet affording a smooth surface capable of receiving printed or hand written inscriptions. As in the first described embodiment, a centrally-allocated bead 12a marks the line of folding and affords a sufficient excess of metal to insure against fracture of the metal 25 incident to opening and closing the card.

While I have herein shown and described cards with but two folds, I do not wish to be so limited since the number of folds may be increased, without changing the inherent characteristics here- 30 inbefore pointed out.

Having thus described my invention, I claim:

1. A folding greeting card comprising super-

posed outside and inside facing sheets, the former of flexible metal foil, united over their normally flat areas; the outside metal sheet being beaded outward along the hinge so as to distribute the flexure over a definite limited width sufficient to assure against fracture by repeated flexure, and accommodate the inside facing when folded as well as when flat.

2. A folding greeting card comprising super- 80 posed outside and inside facing sheets, the former of flexible metal foil, and interposed stiffening sheets, with a hinge interval between their edges, whereby said facing sheets are united over their normally flat areas while left unattached along their folding hinge; the outside metal sheet being beaded outward along the hinge so as to afford a curved hinge zone between the stiffening sheets 85 wider than the corresponding hinge zone of the inner facing and distribute the flexure over a 90 definite limited width sufficient to assure against fracture of the outer hinge zone by repeated flexure.

3. A folding greeting card in accordance with the preceding claim wherein the inside facing is 95 of metal foil and the beading of the outside facing sheet affords room to accommodate flexure of the inside facing sheet without reaction or conflict with the outer.
